UNITED STATES PATENT OFFICE.

GEORGE PUCK, OF LAKEFIELD, MINNESOTA.

MOTOR ATTACHMENT FOR CORN PICKERS.

Application filed March 15, 1926. Serial No. 94,898.

The present invention relates to motor attachments for corn pickers, and more particularly to an attachment made up namely of Ford parts that may be mounted on the well known McCormick-Deering corn picker for propelling the various parts thereof, thus greatly lightening the draft.

Ordinarily it requires five horses or a good sized tractor to pull the McCormick-Deering corn picker, whereas by utilizing my attachment, the lost power of the draft may be greatly decreased, better results obtained, and more easy handling and manipulation.

Another very important object of the invention is to provide an attachment of this nature which may be easily assembled and disassembled in relation to the corn picker, and which is simple in construction, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is a top plan view showing the main frame of a corn picker of conventional construction with my attachment mounted thereon.

Fig. 2 is a side elevation thereof, with the left hand wheel removed.

Fig. 3 is a fragmentary elevation showing the upper and lower stub tongues, and

Fig. 4 is a detail elevation showing the throttle valve controlling means for the carbureter.

Referring to the drawing in detail, it will be seen that 5 designates the axle supported on bull wheels 6 and supporting the main frame 7 on which is journaled in the usual manner the main drive shaft 8 having its

usual clutches 9 controlled in the usual manner. The upper stub tongue 10 extends forwardly in the usual manner and the lower stub tongue 11 is mounted thereon in the usual manner as is indicated at 12. All of

the parts thus far described are conventional and well known in this art, being in actual use on the well known McCormick-Deering corn picker. These conventional parts have been disclosed in detail for the purpose of illustrating the adaptability of my attachment, and the manner in which it is mounted.

The attachment is made up exclusively of Ford parts including the well known engine 14, the drive shaft 15, the differential and axle housing 16, and axle shaft 17. The differential and axle housing extend transversely across the main frame 7, parallel to the main drive shaft 8 and forwardly thereof. One of the axle housings, the left hand one, is cut off short as is also the corresponding axle shaft 17. Sprockets 19 are fixed to the ends of the axle shaft 17 and have trained thereover the usual picker drive chains 20 which, in the present instance, are shortened from the ordinary length, and are trained over the sprockets on the clutches 9 for driving the shaft 8.

The differential and axle housings are held in place by suitable U-bolts 21. The drive shaft 15 extends forwardly to the left hand side of the stub tongue 10 so that the engine 14 is located to the left hand side thereof also. The left hand side of the crank case has an arm 22 extending therefrom and attached to the main frame as at 23. A second arm 24 also extends from the left hand side of the crank case rearwardly and is twisted to be engaged as at 25 with one of the longitudinal members of the main frame. A bracket 26 extends from the left hand side of the radiator under the engine and is attached to the left hand side of the stub tongue 10 as at 27. Another arm 28 extends from the right hand side of the radiator and is attached to the right hand side of the stub tongue 10.

An arm 29 is extended from the right hand side of the crank case and is attached to the right hand side of the stub tongue. A lever 30 is fulcrumed as at 34 and has a link 36 attached to the clutch pedal 33 of the Ford engine, so that said clutch pedal may be held in any of its three well known positions, namely, neutral, low speed, or high speed.

In order to mount the engine as just described, it is necessary that the usual tilting mechanism be removed, as it is on the left hand side of the stub tongues 10 and 11. This tilting mechanism, however, is placed on the right hand side as is clearly shown in Figs. 1 and 2 of the drawings. This tilting mechanism is conventional except for its location, and includes the usual tilting lever 35 pivoted on frame 36 attached to the lower stub tongue 11. The arm 37 of the lever 35 is engaged with the link 38 which is piv-

totally engaged as at 39 with the upper stub tongue 10. In order to hold the throttle valve of the carbureter 40 at a desired adjustment, I utilize a wire 41, guided through 5 a tube 42, and attached to a lever 43 pivoted intermediate its ends as at 44, on an L-shaped plate 46 attached to the engine block by bolt 47.

A threaded member 48 rises from the end 10 of the plate through the lever 43 and a spring 49 is disposed thereon between the plate and the lever for normally holding the valve of the carbureter closed. A nut 50 is threadedly engaged on the member 48 for 15 properly adjusting the lever 43 and consequently the valve of the carbureter 40.

The cheapness, efficiency, and convenience of this attachment, as well as its ease of assembly and disassembly will now be clearly 20 understood by those skilled in this art without a more detailed description thereof. The present embodiment and utility of the invention, has been disclosed in detail, since in actual practice it attains the features of 25 advantage enumerated as desirable in the statement of the invention and the above description.

It will be apparent, however, that changes in the details of construction, and in the combination and arrangement of parts may 30 be resorted to without departing from the spirit or scope of the invention as herein-after claimed, or sacrificing any of its advantages.

Having thus described my invention, what 35 I claim as new is:—

A corn picker including, in combination, a main frame, a drive shaft on the main frame, a stub tongue on the main frame, a second stub tongue below the first stub tongue 40 and pivoted thereto, an engine mounted on the first stub tongue to the left hand side thereof, a main shaft extending rearwardly from the engine alongside of the first stub tongue over the main frame, axle shafts operatively connected with the main shaft, chain drives operatively connected with the axle shaft and with the drive shaft, and a 45 tilting mechanism on the right hand side of the stub tongue. 50

In testimony whereof I affix my signature.

GEORGE PUCK.
